United States Patent Office

Des. 222,170
Patented Oct. 5, 1971

222,170

PLATE OR SIMILAR ARTICLE

Ryotaro Takeoka, Aichiken, Japan, assignor to
Noritake Co., Inc., New York, N.Y.

Filed May 6, 1970, Ser. No. 22,851

Term of patent 7 years

Int. Cl. D7—01

U.S. Cl. D44—15

The figure is a plan view of a plate or similar article showing my new design, a portion of the design being shown between dot and dash lines and a repeat portion being shown between dotted lines.

The plate is of a conventional configuration when viewed from the side and bottom thereof.

I claim:

The ornamental design for a plate or similar article, substantially as shown and described.
